UNITED STATES PATENT OFFICE.

MARTIN MAURER, OF ST. LOUIS, MISSOURI.

DEVICE FOR ORNAMENTING PAVEMENTS.

SPECIFICATION forming part of Letters Patent No. 519,919, dated May 15, 1894.

Application filed May 8, 1893. Serial No. 473,373. (No model.)

To all whom it may concern:

Be it known that I, MARTIN MAURER, of the city of St. Louis and State of Missouri, have invented certain new and useful Improvements in Devices for Ornamenting Pavements, of which the following is a full, clear, and exact description, reference being had to the accompanying drawings, forming a part hereof.

My invention relates to an improved "tool for ornamenting artificial stone" and other forms of pavements during the process of laying the same, and consists in the novel construction, combination and arrangement of parts hereinafter specified and designated in the claims.

In the drawings: Figure 1 is a plan view of my improved tool and a portion of a pavement, illustrating the mode of application in ornamenting a pavement. Fig. 2 is a sectional side elevation of same taken on the line A—A of Fig. 1. Fig. 3 is a sectional side elevation of the improved tool, with the terminal flanges of the cylinder removed but shown in dotted lines, and with parts broken away. Fig. 4 is a detailed section illustrating the manner of mounting the cylinder, with said cylinder indicated in dotted lines.

The object of my invention is to provide an improved hand-tool for ornamenting or laying off artificial stone or other pavements while in a plastic state during the laying thereof, and which tool shall be efficient in operation for such purpose, simple in construction and reasonable in cost.

By the use of my improved tool I produce simultaneously a large number of distinct indentations in the plastic material by a single movement of one of the operator's hands in which the tool is held.

Referring again to the drawings, 1 indicates the main body of the tool, which is preferably in the form of a plain cylinder having squared ends, a smooth outer periphery and a longitudinal bore 2.

3 indicates a series of separate sections curved transversely to conform to the outer periphery of the body 1, and having radial meeting edges in contact, so that when all the sections are united and placed in position upon said body they form a cylindrical shell thereon having the definite construction hereinafter mentioned. Each of the sections 3

has a connecting series of projections 4 upon its outer surface, forming a determinate portion of a definite design, in relief, upon said outer surface, arranged to connect with other definite portions of adjacent sections, and form a complete cylinder with a definite and complete design upon its outer surface, adapted to indent in a plastic surface when said cylinder is rolled upon the same. Each of the sections 3 has also an integral terminal flange 5 in the form of a segment at each terminal thereof, the same projecting above the outer surface of each and uniting with the flange 6 of adjacent sections to form complete annular terminal flanges upon the cylinder projecting beyond the outer surface thereof.

6 indicates a spindle which loosely engages in the bore 2 of the body 1 and has its opposite ends squared and provided with a threaded bore 7 in which is located a screw 8 having a thread upon its inner portion and a plain outer surface 9.

10 indicates a U-shaped yoke, the arms of which are provided with perforations or bearings 11 which are loosely engaged by the smooth surface 9 of the screws or bolts 8. Said yoke 10 is thus loosely mounted upon the spindle 6. Loosely mounted upon said spindle between each of the arms and the adjacent end of the body 1 is a washer 12. The complete cylinder constructed as above described, is thus loosely mounted to revolve within the yoke 10. A handle 13 has one of its ends secured to the yoke 10 centrally of the length thereof, by means of a suitable bolt 14 and a nut 15, so that said handle projects from the outer surface of said yoke at a right angle thereto.

The series of sections 3 may be secured in the above described position upon the cylindrical body 1 in any known manner, such for instance as by means of screws or bolts 16 having a threaded inner portion and passed through countersunk openings 17 formed in each of said sections and engaging threaded openings 18 in said body 1, so that the heads of said bolts or screws will be flush or below the outer surface of each section.

The body 1, as well as all the parts of my improved tool, is made of metal and solid, so as to embody as much weight as possible, as the weight of the tool should be such as to

sink the projections 4 their full depth into the plastic compound and bring the smooth intervening spaces upon the outer surface of the sections into contact with the surface of the plastic compound.

- 5 The operation is as follows: 19 indicates a body of plastic compound, such as plastic paving compound, laid upon a suitable foundation 20 of cinders or other material. This 10 material is first provided with a smooth unbroken upper surface, and then the improved tool is rolled over this surface while same is in a plastic condition, by means of the handle, 14 and the projections 4 will engage 15 said plastic material and produce upon its surface corresponding indentations, and as the forward movement of the tool continues, a complete and definite design will thereby be produced upon the plastic compound, the 20 sectional cylinder rolling over and over continuously. Simultaneously with the operation of indenting the design in the plastic compound, the terminal flanges 5 will produce a straight border line or indentation 25 21 at each marginal edge of the design thus produced. Likewise, additional designs may be formed in the plastic body alongside of and parallel with the previously formed design, by placing the annular flange 5 of one 30 end of the sectional cylinder in engagement with the separate border line 21 previously formed. By proper attention upon the part of the operator he may make the succeeding designs merge into and correspond with the 35 configurations of the preceding design, so as to form a complete ornamental surface upon the plastic body having a width many times in excess of the length of the cylindrical body 1.
- 40 I have found in practice that my improved tool is very efficient in the operation above described, making with one movement or stroke of the hand a large number of marks or indentations in the plastic material.
- 45 I prefer to make the sectional cylinder about one foot in length, so as to retain its size and weight within such bounds that the tool may be readily handled by a single operator.
- It will be seen that this tool is entirely independent of exterior devices.

I am aware that prior to my invention a roller for marking designs in artificial stone had been constructed with a marking surface in detachable sections, held in place by rings threaded upon the ends of the roller, and I 55 therefore, do not claim such as my invention.

What I claim is—

1. The improved tool for ornamenting artificial stone, comprising a main body 1 in the form of a plain cylinder having squared ends, 60 a smooth outer periphery and a longitudinal bore 2, a series of separate sections 3 curved transversely to conform to the outer periphery of said body, and having radial meeting edges in contact, each of said sections having 65 a connecting series of projections 4 upon its outer surface forming a determinate portion of a definite design in relief, and each section having an integral flange 5 in the form of a segment at each terminal thereof, the same 70 projecting beyond the outer surface of the section which carries it and uniting with the flange of adjacent sections to form complete annular terminal flanges, a spindle engaging the bore of said body, and a suitable handle 75 applied to said spindle, substantially as herein specified.

2. The combination, in a tool for marking artificial stone, of a main body or roller carrying designs in relief upon its outer periphery, and having a longitudinal-bore 2, a spindle 6 mounted in said bore and having its ends squared and provided with a threaded bore 7, screws 8 having threads upon their inner portions and the plain outer surface, and engaging 80 said bores 7 of said spindle, a U-shaped yoke 10, the arms of which are provided with perforations or bearings 11 loosely engaged by the smooth surfaces 9 of said screws or bolts 8, a washer 12 loosely mounted upon said spindle 90 between each of the arms of said yoke and the adjacent end of said body, and a handle applied to said yoke, substantially as herein specified.

In testimony whereof I affix my signature in 95 presence of two witnesses.

MARTIN MAURER.
